UNITED STATES PATENT OFFICE.

NANCY J. GRAHAM, OF JACKSON, OHIO.

HEATER ATTACHMENT FOR STOVES.

SPECIFICATION forming part of Letters Patent No. 269,047, dated December 12, 1882.

Application filed July 29, 1882. (No model.)

To all whom it may concern:

Be it known that I, NANCY J. GRAHAM, a citizen of the United States, and a resident of Jackson, in the county of Jackson and State of Ohio, have invented a new and valuable Improvement in Heater Attachments for Stoves; and I do hereby declare that the following is a full, clear, and exact description of the construction and operation of the same, reference being had to the annexed drawings, making a part of this specification, and to the letters and figures of reference marked thereon.

Figure 1 of the drawings is a representation of this invention in a perspective view. Fig. 15 2 is a vertical section, showing the bake-oven with the bake-pan inside. Figs. 3, 4, 5, 6, and 7 are details in perspective.

The object of my invention is to conduct a portion of the heat from a stove located in an 20 apartment on one floor of a building up to an apartment on the floor above, and to utilize the heat thus conducted to the upper apartment for baking or other culinary purposes. To such end I conduct from the stove up 25 through the floor above a hot-air pipe, and at the upper terminus of said pipe I arrange a small oven, in which a bake-pan can be placed, the ascending heat circulating around the pan and then passing out into the room.

Referring to the drawings, let A indicate an 30 apartment on the first floor, B, and C an apartment on the second floor, D, of a dwelling.

E indicates an ordinary open-front stove, located on the first floor, for heating the room, 35 as usual. The hot-air pipe F enters this stove preferably at one side thereof, and passes under the grate, after which it is carried up through the second floor. The supply of air for this pipe is derived from the lower room 40 or apartment, and in order to effectively heat the same the pipe is provided with an enlargement, f, below the grate of the stove;

or the pipe can be coiled flat under the grate before it is carried up. The oven G, which is supported at the upper terminal of this pipe, 45 consists of a sheet-metal case, preferably approximating in shape to a bake-pan, and provided with a lid or cover, H. The hot-air pipe opens into the bottom of said oven, and in the lid is a short hot-air-escape pipe, I, so that the 50 hot air entering the oven will pass out through the escape-pipe into the room and warm the same.

K indicates an ordinary bake-pan, placed within the oven. In order to raise the bake-pan above the bottom of the oven, so as to allow the hot air to enter and circulate under the pan, I provide a stand, L, consisting of a perforated or open-work plate provided with legs l, which rest upon the bottom of the oven. 55 The pan is seated upon this stand or rest, which not only allows the air to circulate under the bake-pan, but also by reason of its perforations or openings allows the hot air to come into direct contact with the bottom of the pan. The 60 hot air circulates freely under, around, and over the pan, and then passes out through the escape-pipe.

Having thus described my invention, what I claim is—

In stoves, the combination of pipe F, provided with enlargement f, and extended from the stove upward through one or more floors of a building, the oven G, having lid H, and escape-pipe I, constructed and arranged substantially as and for the purposes specified.

In testimony that I claim the above I have hereunto subscribed my name in the presence of two witnesses.

NANCY JANE GRAHAM.
